Attorney

UNITED STATES PATENT OFFICE.

MARION LEUCHTAG, OF NEW YORK, N. Y.

BRASSIERE.

Application filed May 31, 1927. Serial No. 185,529.

This invention relates to wearing apparel, and more particularly to an improved brassière or bust supporting form.

To that end the invention chiefly contemplates a novel and useful bust supporting form, as distinguished from the bandage-like brassière ordinarily used for bust supporting purposes, the invention particularly having in view a simple device of that kind which is not only susceptible of being made in a very attractive way so as to possess special utility with evening clothes, as an accessory to the dress, but also held to the body in a manner so as to give natural form and appearance to the bust without danger of displacement in any direction, thus entirely dispensing with the necessity of the undesirable and troublesome shoulder straps.

A further object of the invention is to provide a device that may be readily fitted in place by fastening the same at the front, and which when in use will possess sufficient adaptability and resiliency to hold itself in proper place and to yield to natural body movements. That is to say, it is proposed to provide a construction in which the supporting member includes an elastic back section adapted to be adjusted to suit the convenience of the wearer, and a separable flat and unobtrusive front connection, thereby avoiding at the front the use of the ribbon tie or the like which requires a projecting or bunchy bow-knot as a fastening.

A still further object of the invention is to provide a back supporting strap so arranged as to hold the breast supporting members in proper position, preventing displacement of the device under the movements of the body and also preventing chafing.

With the above and other objects in view which will more readily appear as the nature of the invention is better understood, the same consists in the novel construction, combination and arrangement of parts hereinafter more fully described, illustrated and claimed.

Fig. 1 is a view illustrating the application of the invention.

Fig. 2 is an inside elevation thereof.

Fig. 3 is a vertical sectional view taken on the line 3—3 of Fig. 2.

Fig. 4 is a detail sectional view of the front fastening.

Fig. 5 is a detail horizontal sectional view of the adjustable back fastening.

Fig. 6 is an enlarged detail view illustrating the front fastening more clearly.

Similar reference characters designate corresponding parts throughout the several figures of the drawings.

In carrying the present invention into effect it is proposed to provide a pair of breast forms or members designated generally as 1 and each including a semi-rigid frame 2, preferably of wire or the like encased with a suitable covering, and having secured thereto the fabric cover-piece 3 which may be provided with any suitable and desirable ornamentation, and form a flexible form and breast support which is maintained in shape by the ring or frame 2. These cover-pieces loosely fill the frame rings and necessarily are of a cupped formation to fit the form and also necessarily may be made in any ornamental or attractive manner and with any kind of fabric to have the same harmonize in color and dress making effects with the lingerie or garments to be worn in connection therewith.

The said form members 1—1 are connected at their front edges by means of the fastening connections A, each of which include the tape or strip members 4 and 5 which connect with the ring or frame 2 of each member 1 respectively at opposite sides of a plane intersecting the circumference of the rings and the point of fastening. The front portions of the members A are provided with a suitable form of fastening device which will permit of a flat connection between the two parts, for example a hook and eye a. A fastening of this type is used in preference to a bow-knot because of the bulkiness of the latter, and a snap fastener would not be as desirable because it would be liable to become unfastened under the breathing movements of the body.

The outside edges of the rings 2 are connected by a main supporting or back belt 100 designated generally as B. This belt preferably includes the elements 6 and 7 which are connected at one end in spaced relation to the rings 2 at opposite sides of the midway point thereof, while their other ends are joined together as indicated at 8. The said ends 8 have secured thereto by stitching or otherwise an adjustable elastic section 9.

This elastic section preferably includes an adjustable loop of conventional form which permits of making the adjustable section longer or shorter if desired to suit the convenience of the wearer.

With the device in the form shown in Figs. 1 and 2 it will be apparent that after the main belt B has been set or adjusted to the proper length, the matter of putting on and taking off the device merely amounts to fastening and unfastening the front members A by disengaging the hook and eye α . Also by reason of the fact that the front fastening sections A and the belt B connect with the rings 2 in such a way that the ring is prevented from turning or rotating, a firm and positive support to the bust is afforded without discomfort and annoyance due to the shifting or twisting of the members 1 when in use. Furthermore, by reason of the novel arrangement of parts which includes the elastic and adjustable belt B and the front fastening A, the entire device is fitted to the body with sufficient snugness so that shoulder straps are unnecessary, thereby permitting of the use of the brassière with evening gowns or dresses where shoulder straps are undesirable.

Without further description it is thought that the features and advantages of the invention will be readily apparent to those skilled in the art, and it will of course be understood that changes in the form, proportion and minor details of construction may be resorted to, without departing from

the spirit of the invention and scope of the appended claims.

I claim:

1. A brassière comprising a pair of breast forms each consisting of a relatively stiff frame ring, and a cupped fabric cover-piece loosely filling the frame ring and secured thereto, a back-embracing belt having diverging attaching members connecting with the frame rings respectively above and below the horizontal axis thereof, and a separable flat front connection having diverging attaching members respectively connecting with the frame rings respectively above and below the said horizontal axis thereof.

2. A garment of the class described comprising in combination, supporting members including semi-rigid rings and cupped fabric cover-pieces loosely filling the frames and secured thereto, a back encircling belt member including spaced members connected to said rings respectively at points on each side of the horizontal midway portion thereof, and separable fastening means for connecting the inside portions of the supporting members, said fastening means each comprising strip members of substantially V-shaped formation having a separable fastener at their apices and having the ends opposite their apices connected with the semi-rigid rings of the supporting members.

In testimony whereof I hereunto affix my signature.

MARION LEUCHTAG.
